NOZZLE FOR THE DISCHARGE OF LIQUIDS

Thomas A. Henshaw, Elland, England, assignor
to Nu-Swift, Limited, London, EnglandApplication March 5, 1948, Serial No. 13,137
In Great Britain March 11, 1947

5 Claims. (Cl. 299—141)

1

My invention is or relating to nozzles for the discharge of liquids has particular reference to nozzles for the discharge of liquid fire-extinguishing media, but a nozzle according to or embodying the invention is, as will be apparent from the description to be hereinafter given, applicable with advantage for other purposes.

An object of the invention is to provide an improved construction of nozzle designed to give, at will, a discharge in the form of a jet, or of a spray, or what may be termed a fog or mist, that is to say a spray of exceedingly fine division.

A further object is to provide a nozzle of such construction that even when dealing with flows of large volume and at high pressure the change from one form of discharge to another can be made with a minimum of effort.

My improved nozzle is characterized by the interposition between the conduit through which the liquid to be discharged is led to the nozzle, and what may be termed a circumferentially-adjustable discharge-controller, of a flexible diaphragm formed with a series of openings into, or away from, complete or partial coincidence with which a series of passages through the discharge controller can be brought, the openings in the flexible diaphragm being so disposed and the passages through the discharge controller being so formed that by appropriate circumferential adjustment or rotation of the controller either a solid jet, or a spray of any desired fineness down to what may be termed a mist or fog can be discharged. It may be arranged that at all times a passage-way, preferably centrally disposed, will be afforded through the flexible diaphragm and discharge controller, in which case the nozzle will be incapable of use as a shut-off valve. If such a valve is required it may be included in the pipe or conduit leading to the discharge nozzle, or alternatively the passages in the discharge controller may be so disposed that the discharger itself constitutes a simple shut-off valve.

In the accompanying drawing,

Fig. 1 is a sectional elevation of a nozzle according to one embodiment of the invention; and

Fig. 2 is a similar view to Fig. 1, but having the section taken on a different plane;

Fig. 3 is an end view of the nozzle, looking in the direction of the arrow 3 in Fig. 1;

Fig. 4 is a diagram showing a somewhat different arrangement of the ports or passages from that in the nozzle shown in Figs. 1-3.

Referring to the drawings, and firstly to Figs. 1 to 3, *a* represents a nipple adapted to be secured on the end of a delivery pipe, and *b* what

may be termed a retaining member, screwed on to the nipple *a* and having a shoulder *b'* between which and the extremity of the nipple there is clamped the peripheral portion of a flexible diaphragm *c* of suitable material, having a central opening *c'* and other openings *c²*, *c³*, *c⁴* and *c⁵* which will be referred to later:

On the outer side of the diaphragm *c* is a part *d* which we shall refer to as a rotatable drum.

10 This drum is held to the nipple *a* by means of an inwardly-extending flange *b²* on the retaining member *b*, said flange acting through ball-thrust bearing *e* on a collar *f* screwed on to the inner end of the drum *d*. In the case of a relatively small nozzle the ball-thrust bearing *e* may be omitted or, it may be, replaced by a simple bearing.

The drum *d* has a central passage-way *d'* and, in the illustrated embodiment, six circumferentially-spaced passages *d²*, *d³*, *d⁴*, *d⁵*, *d⁶* and *d⁷* which extend parallel to the central passage *d'*. The passages *d²* and *d³* are turned inwardly at their outer ends and lead at diametrically-opposed points into the central passage *d'* as shown in Fig. 1. The other four passages *d⁴*, *d⁵*, *d⁶* and *d⁷* of the drum are furnished at their outer ends, as shown in Fig. 2, with removable nipples *g* each having two small orifices *g'* and *g²* inclined towards one another at a suitable angle.

30 If the drum *d* is rotated to a position in which the passages *d²* and *d³* are aligned with the openings *c²* and *c³* in the flexible diaphragm *c*, streams of water flow along the said passages and on emerging from the inwardly-directed outer ends 35 of the passages strike the central jet emerging from the central passage *d'* and break it up into spray.

If the drum is rotated to a position in which its passages *d⁴*, *d⁵*, *d⁶* and *d⁷* are aligned with the openings *c²*, *c³*, *c⁴* and *c⁵* in the diaphragm *c*, the passages *d²* and *d³* are closed and water flows through the passages *d⁴*, *d⁵*, *d⁶* and *d⁷* to be converted into a very fine mist or fog by means of the nipples *g*. There is thus provided around the central jet emerging from the passages *d'* a shield of mist or fog which serves to protect the operator handling the nozzle.

40 If the drum is rotated to a position in which all its passages *d²-d⁷* are out of alignment with the openings *c²-c⁵* of the diaphragm *c* a solid central jet only is provided.

The drum *d* may be provided with a handle, hand wheel, projection or projections, or be otherwise suitably fashioned to facilitate its rotation.

The flexible diaphragm acts as a seal to prevent leakage through such passages in the drum as it is desired to close, the pressure of the liquid assisting to make the seal.

The nipples *g* are made removable for purposes of cleaning and inspection. In order to prevent clogging of the relatively fine outlets of the nipples a filter in the form of a sheet of fine gauze may be inserted behind each filter as indicated at *h* in Fig. 2.

An advantage of the construction shown in Figs. 1 to 3 is that a constant outlet is provided through the nozzle even if the spray or fog passages become clogged up.

In Fig. 4 an arrangement is shown in which what we have termed the central opening in the diaphragm and the central passage in the rotatable drum are offset from the centre. In the diagram the openings of the flexible diaphragm are indicated in broken line and those of the rotatable drum in full line. As will be seen from the diagram the rotatable drum can be positioned so that all its passages are closed, the drum thus acting as a shut-off valve. By appropriate rotation the passages *d*⁴-*d*⁷ can be positioned opposite the openings *c*²-*c*⁵ of the diaphragm, leaving the passage *d*' closed and thus providing fog or mist only. In another position of the drum the passage *d*' can be opened up as well as the passages *d*⁴-*d*⁷ thus providing a solid jet surrounded by fog or mist.

In still another position the passage *d*' alone can be opened up thus affording only a solid jet whilst in another position the passage *d*' and the passages *d*² and *d*³ can be opened up thus affording a spray. The rotatable drum in this embodiment constitutes, as will be seen, a simple shut-off valve.

If desired, either the spray passages *d*² and *d*³ or the fog passages *d*⁴-*d*⁷, or the jet passage *d*' may be omitted.

Having thus described my invention, what I claim as new and desire to secure by Letters Patent is:

1. A liquid discharge nozzle, comprising in combination, a nipple adapted to be secured to the end of a liquid discharge pipe; a retaining member secured to said nipple, the said retaining member having a central outlet channel; a diaphragm disposed across said central outlet channel; a central opening provided in said diaphragm; a series of angularly spaced openings arranged in said diaphragm around said central opening; a single rotatable drum held on said retaining member for rotation relatively thereto and with one end face in contact with said diaphragm; a central passageway provided in said drum; a series of circumferentially spaced passages provided around said central passageway in said drum and extending parallel to said central passageway, at least two of said passages being turned inwardly at their outer ends and leading at diametrically opposite points into said central passageway; nipples removably associated with said drum across the outer ends of the other of said passages; and small angularly directed orifices formed in said nipples whereby in one position of the drum liquid is permitted to pass only through the central passageway of the drum, in another position liquid is permitted to pass through the central passageway of the drum and through the passages of the drum, the outer ends of which lead at diametrically opposite points into the central passageway of the drum, while in a third position of the drum liquid is permitted to pass through the central passageway of the drum and through these passages through the drum, the outer ends of which register with the angularly directed orifices.

65

4. A nozzle constructed in accordance with claim 1 wherein the said retaining member and drum are provided with overlapping flanges and wherein a bearing is disposed between said overlapping flanges to permit rotation of said drum.

5. A liquid discharge nozzle, comprising in combination, a nipple adapted to be secured to the end of a liquid discharge pipe; a retaining member secured to said nipple, the said retaining member having a central outlet channel; a diaphragm disposed across said central outlet channel;

to pass through the central passageway of the drum and through these passages through the drum, the outer ends of which register with the angularly directed orifices.

5 2. A liquid discharge nozzle, comprising in combination, a nipple adapted to be secured to the end of a liquid discharge pipe; a retaining member secured to said nipple, the said retaining member having a central outlet channel; a diaphragm disposed across said central outlet channel; a central opening provided in said diaphragm; a series of angularly spaced openings arranged in said diaphragm around said central opening; a single rotatable drum held on said retaining member for rotation relatively thereto and with one end face in contact with said diaphragm; a central passageway provided in said drum; a series of circumferentially spaced passages provided around said central passageway in said drum and extending parallel to said central passageway; and means associated with said drum forming small angularly directed outlet orifices of a narrowed diameter at the outer ends of the other of said passages whereby in one position of the drum liquid is permitted to pass only through the central passageway of the drum while in another position liquid is permitted to pass through the central passageway of the drum and through the passages, the outer ends of which register with the angularly directed orifices.

3. A liquid discharge nozzle, comprising in combination, a nipple adapted to be secured to the end of a liquid discharge pipe; a retaining member secured to said nipple, the said retaining member having a central outlet channel; a diaphragm disposed across said central outlet channel; a central opening provided in said diaphragm; a series of angularly spaced openings arranged in said diaphragm around said central opening; a single rotatable drum held on said retaining member for rotation relatively thereto and with one end face in contact with said diaphragm; a central passageway provided in said drum; a series of circumferentially spaced passages provided around said central passageway, at least two of said passages being turned inwardly at their outer ends and leading at diametrically opposite points into said central passageway; nipples removably associated with said drum across the outer ends of the other of said passages; and small angularly directed orifices formed in said nipples whereby in one position of the drum liquid is permitted to pass only through the central passageway of the drum, in another position liquid is permitted to pass through the central passageway of the drum and through the passages of the drum, the outer ends of which lead at diametrically opposite points into the central passageway of the drum, while in a third position of the drum liquid is permitted to pass through the central passageway of the drum and through these passages through the drum, the outer ends of which register with the angularly directed orifices.

60

4. A nozzle constructed in accordance with claim 1 wherein the said retaining member and drum are provided with overlapping flanges and wherein a bearing is disposed between said overlapping flanges to permit rotation of said drum.

5. A liquid discharge nozzle, comprising in combination, a nipple adapted to be secured to the end of a liquid discharge pipe; a retaining member secured to said nipple, the said retaining member having a central outlet channel; a diaphragm disposed across said central outlet channel;

70 75

central opening provided in said diaphragm; a series of angularly spaced openings arranged in said diaphragm around said central opening; a single rotatable drum held on said retaining member for rotation relatively thereto and with one end face in contact with said diaphragm; a first passageway provided in said drum, the said first passageway being offset relatively to said first opening in said diaphragm; a series of circumferentially spaced passages provided around said first passageway in said drum and extending parallel thereto, at least two of said passages being turned inwardly at their outer ends and leading at diametrically opposite points into said first; and means associated with said drum forming small angularly directed outlet orifices of a narrowed diameter at the outer ends of the other of said passages, whereby in one position of the drum liquid is permitted to pass only through the first passageway of the drum, in another position liquid is permitted to pass through the first passageway of the drum and through the passages of the drum, the outer ends of which lead at

diametrically opposite points into the first passageway of the drum, while in a third position of the drum liquid is permitted to pass through the first passageway of the drum and through these passages through the drum, the outer ends of which register with the angularly directed orifices.
